UNITED STATES PATENT OFFICE.

ARMIN HENRY PIKLER, OF MONTCLAIR, NEW JERSEY, ASSIGNEE TO CROCKER-WHEELER COMPANY, OF AMPERE, NEW JERSEY, A CORPORATION OF NEW JERSEY.

ELECTROMAGNETIC APPARATUS.

No. 841,488.

Specification of Letters Patent.

Patented Jan. 15, 1907.

Application filed April 30, 1906. Serial No. 314,350.

To all whom it may concern:

Be it known that I, ARMIN HENRY PIKLER, a subject of the Emperor of Austria-Hungary, and a resident of Montclair, county of Essex, 5 and State of New Jersey, have invented certain new and useful Improvements in Electromagnetic Apparatus, of which the following is a specification.

This invention relates particularly to the 10 mechanical organization of transformers, induction-coils, and similar electromagnetic apparatus wherein an electric circuit is interlinked with a magnetic circuit.

The object of the invention is to organize 15 and combine the core and electric coils of such a structure with suitable supporting and connecting elements whereby the core and coils are readily assembled, suitably insulated, and securely held together, with proper 20 provision for such uncertainty and variability in the sizes of coils as are liable to arise when wound with specific electrical objects in view.

A further object of the invention is to provide 25 for such variations in size as arise from temperature changes through electrical or other causes.

In the accompanying sheet of drawings, which forms a part of this application, Figure 1 is a side elevation of a core-type transformer embodying my invention, in which the coils on one leg of the transformer and one end of each of the clamping-frames for the coils are broken away. Fig. 2 is an edge 35 view of the same. Fig. 3 is a top view of the same, in which the upper yoke of the core is broken away at one end. Fig. 4 is a perspective view of one of the brackets, which are adjustably fastened at the sides of the 40 yokes and support the clamping-frames for the coils.

The transformer as illustrated comprises two sets of high-tension coils H H and two sets of low-tension coils L L and a rectangular core-frame separable into four parts, two of the parts being parallel legs l l, on each of which is a set of low-tension coils and a set of high-tension coils, and the other two parts being yokes b b, which lie against the ends of 45 the legs and close the magnetic circuit. Each of the four parts of the core-frame is 50 formed of steel sheets firmly bolted together. The legs are each formed of sheets of three

different widths and in several groups which are stepped so that their exterior corners will 55 form elements of the cylinder closely fitting the interiors of cylindrical insulating-tubes t t and leaving ventilating or oil ducts in the re-entered angles between the corners. The steel plates or laminations may also be spaced apart at the center of the cores for additional 60 ventilating or oil ducts. The contacting surfaces forming joints between the legs and yokes are preferably surfaced by milling or planing, so that they may fit accurately, and the resistance to magnetic flux will be small. Dowels are inserted to insure proper positioning and alignment of the parts of the core-frame. Plates p p are laid on the sides of the yoke-places and clamp the laminations, 70 being drawn together by insulated bolts which pass through the plates and laminations. Tension-bolts K K hold clamping-bars J J on the yokes and hold the several parts of the core firmly together in a rigid 75 structure which is utilized as a foundation for the support of the other parts.

The high-tension coils are concentric with and exterior to the low-tension coils, so that they may be spaced therefrom for ventilating or for oil circulation.

Owing to the separable character of the core-frame all the coils may be formed or wound apart from the core and assembled on the legs thereof after winding.

The high-tension coils are supported and clamped between frames F F, preferably of wood, at each end of the coils. Brackets B B project from the yokes of the core, and set-screws R R in the brackets at one end 90 bear against springs S S, placed between them and the frame at that end. The springs automatically take up all small changes in the thickness of coils arising from contraction and expansion due to temperature variations and prevent them from becoming loose and protect them from stresses that would be injurious to their insulation. The brackets are shown as separate parts from the plates at either side of the yokes, 100 and they are held to the yokes by bolts which pass through vertically-disposed slots in the brackets to admit of a greater range of adjustment than is conveniently provided by the set-screws.

The low-tension spool on each leg of the

core is close-fitting and does not require such special clamping means as are provided for the high-tension coils.

What I claim as new, and desire to secure 5 by Letters Patent of the United States, is—

1. In an electromagnetic apparatus, the combination with a core and windings thereon, of clamping-frames for the windings, connecting parts between the clamping-frames, and elastic devices interposed in said connecting parts, substantially as described.

2. In an electromagnetic apparatus, the combination with a core and windings thereon, of clamping-frames for the windings, brackets adjustably supported by the core,

and connections between the brackets and clamping-frames, substantially as described.

3. In an electromagnetic apparatus, the combination with a core and windings thereon, of clamping-frames for the windings, 20 brackets adjustably supported by the core, and elastic connections between the brackets and clamping-frames, substantially as described.

Signed by me at East Orange, New Jersey, the 25th day of April, 1906.

ARMIN HENRY PIKLER.
